[57] CLAIM

The ornamental design for a test specimen holder, as shown and described.

DESCRIPTION

FIG. 1 is a perspective view of a test specimen holder showing my new design, the holder being in the assembled rolled condition for the testing process;

FIG. 2 is a top plan view thereof, the holder being flat and unrolled for the ease of mounting the test specimens, the bottom view being identical;

FIG. 3 is an enlarged end elevational view of the clip which maintains the holder in the rolled condition;

FIG. 4 is an end elevational view of the holder as shown in FIG. 1;

FIG. 5 is a side elevational view of the holder as shown in FIG. 1.
